(57) **CLAIM**

The ornamental design of a tabbed prosthesis insertion below.

DESCRIPTION

FIG. 1 is a top right perspective view of an ornamental design for a tabbed insertion bellow, with the small tab shown folded; FIG. 2 is a top plan view thereof;

FIG. 3 is a bottom plan view thereof;

FIG. 4 is a left side elevation view thereof;

FIG. 5 is a right side elevation view thereof;

FIG. 6 is a distal end elevation view thereof;

FIG. 7 is a proximal end elevation view thereof;

FIG. 8 is an environmental front perspective view of the bellow inserted;

FIG. 9 is a cross sectional view thereof along line 9-9 of FIG. 8.

FIG. 10 is a cross sectional view along line 9-9 of FIG. 8 showing the small tab extended;

FIG. 11 is a top proximal perspective view of the bellow, showing the small tab folded;

FIG. 12 is a top proximal perspective view of the bellow, showing the small tab extended; and,

FIG. 13 is a bottom plan view of the bellow, showing the small tab extended.

The broken line showing of parts of the drawings is included for the purpose of illustrating use and environment and forms no part of the claimed design.
